TELESCOPABLE LOG HOLDER

Raymond L. Hetu, 7 Sonora Drive,
Chelmsford, Mass. 01824

Filed Jan. 17, 1969, Ser. No. 15,388

Term of patent 14 years

Int. Cl. D23—03

U.S. Cl. D23—98

Fig. 1.

Fig. 2.

Fig. 3.

Fig. 4.

FIGURE 1 is a perspective view of a telescopic log holder of my new design.

FIGURE 2 is a front elevational view thereof.

FIGURE 3 is a side elevational view thereof, and

FIGURE 4 is a plan view of the log holder as it appears when disassembled for shipment and display.

The broken line showing of the logs in FIGS. 2 and 3 is for illustrative purposes only.

I claim:

The ornamental design for a telescopic log holder, as shown and described.
